UNITED STATES PATENT OFFICE.

HEINRICH RAAB, OF PIRMASENS, GERMANY.

SHOE MACHINERY.

1,105,834.

Specification of Letters Patent. Patented Aug. 4, 1914.

Application filed January 27, 1913. Serial No. 744,462.

To all whom it may concern:

Be it known that I, HEINRICH RAAB, citizen of Germany, subject of the King of Bavaria and Emperor of Germany, residing at Lembergerstrasse 64, Pirmasens, in the Kingdom of Bavaria and Empire of Germany, have invented new and useful Improvements in and Relating to Shoe Machinery, of which the following is a specification.

The present invention relates to shoe machinery and more particularly to a machine for polishing and decorating the edges of the soles of boots or shoes in any desired manner by the employment of corresponding polishing and decorating tools.

The object of the invention is to provide an improved machine of the above character which shall be simple in construction and efficient in operation.

The invention is illustrated in the accompanying drawing of which—

Figure 1 is a view in front elevation, of the interior of a preferred form of machine embodying the invention, Fig. 2 being a sectional view on the line A—A of Fig. 1.

Referring now to the drawing, a tool holder or clamp is indicated at *m* as rigidly secured to a shaft *k* by means of arm 1 which is adapted to be rocked or oscillated about the axis of the shaft *k*. In order to effect such rocking or oscillating movement a prismatic cam member or disk *d* is provided having diametrically opposite to each 35 projecting portion a portion of smaller radius and being mounted for rotation within the cast-iron casing *a* of the machine which is provided with a cover *b* secured by bolts *c*. The disk *d* is preferably in cross section, a regular polygon having an odd number of sides, for instance seven, and the periphery of the disk is adapted to engage with rollers *f* which are pivotally mounted at the extremities of a pair of arms or levers 45 *g*. The other extremities of the arms *g* are pivoted at *h* upon a rocker *i*, a hole in which fits on to a coned surface on the shaft *k* and is secured in position by means of a nut, so that the members *i*, *k*, *l* and *m* are rigidly 50 secured together. In order to cause the rocking movement of the shaft *k* the prismatic disk *d* which is mounted upon a shaft *q* is arranged to be rotated by means of a belt pulley *e*. The rotating rollers *f* follow 55 the external periphery of the disk *d* thereby correspondingly moving the arms *g*. The

rocker *i* is provided with two arms or extensions each of which is provided with a stud *s* adapted to engage resiliently with the arms *g* by means of springs *r* interposed between the arms *g* and the arms of the rocker *i*. When it is desired to stop the machine a spring-controlled pin *p* which normally engages with a groove *o* on the shaft *k*, is withdrawn and the shaft *k* with the parts secured thereto is moved forward by means of a handle located on the arm *l* until the pin *p* snaps into position within another groove *n*. As shown in the drawings, the rocker *i* is recessed to receive the pivoted ends of the arms, thereby providing sufficient play for enabling the necessary movement. When the shaft *k* with the rocker and the arms *g* is shifted into inoperative position, the arms *g* rest upon the front edges of the walls of the recesses, and are thereby prevented from contacting with the front part of the disk *d*, which is circular and is of smaller diameter than the polygonal part thereof.

Various modifications of the mechanism above described may evidently be adopted without exceeding the scope of the invention.

Having now described my invention what I claim and desire to secure by Letters Patent of the United States is:

1. In a machine for polishing or decorating the edges of shoe soles, a shaft, a tool holder mounted on said shaft, a rocker fixed to said shaft, a rotatable cam member, levers pivotally connected to the rocker projecting parts on said levers, and means for holding said projecting parts of the levers in engagement with the periphery of said cam member and for transmitting the motion of the levers to the rocker, said cam member having opposite to each projecting part a part of smaller radius.

2. In a machine for polishing or decorating the edges of shoe soles, the combination of a shaft, a tool holder mounted on said shaft, a rocker fixed to said shaft, two levers pivotally connected to said rocker, rollers journaled to the ends of said levers, a rotatable disk, and means for holding said rollers in engagement with the periphery of said disk and for transmitting the motion of said levers to said rocker, said disk being in the form of a regular polygon with an odd number of sides.

3. In a machine for polishing or decorat-

ing the edges of shoe soles, the combination of a shaft, a toolholder mounted on said shaft, a rocker fixed to said shaft, projections on said rocker, a rotatable disk, levers 5 pivotally connected to the rocker projecting parts connected with said levers and engaging the periphery of the disk, said disk being in the form of a regular polygon with an odd number of sides, and springs inter- 10 posed between said projections of said rocker and the levers and operating to press the levers against the periphery of the disk.

4. In a machine for polishing or decorating the edges of shoe soles, a shaft, a tool 15 holder mounted on said shaft, a rocker fixed on said shaft, a rotatable cam member, two levers pivotally connected to said rocker, rollers journaled to the ends of said levers, springs interposed between said levers and 20 the rocker for holding said rollers in engagement with the cam member, said cam

member having the shape of a regular polygon with an odd number of sides and said shaft being movable with the tool holder, the rocker and levers fixed thereto longitudinally of its axis, said shaft having two spaced annular grooves therein, and a spring controlled pin carried by the machine casting and adapted to engage one of said grooves to hold the shaft with the levers 25 fixed thereto in operative position relative to said cam and being adapted to engage the other of said grooves to hold the shaft with the levers fixed thereto in inoperative position with respect to the cam. 30

In testimony thereof I have hereunto set my hand in presence of two subscribing witnesses.

HEINRICH RAAB.
